POLYFLUOROPHENYL PHOSPHATE ESTERS
Christian A. Seil, Santa Monica, Robert H. Boschan, Los Angeles, and James P. Holder, Woodland Hills, Calif., assignors to McDonnell Douglas Corporation, Santa Monica, Calif., a corporation of Maryland
No Drawing. Filed May 4, 1964, Ser. No. 364,787
12 Claims. (Cl. 260—955)

This invention relates to certain polyfluorophenyl phosphate esters and is particularly concerned with the provision of a novel class of pentafluorophenyl phosphates.

It is an object of the present invention to provide a series of compounds having high fire resistance, high temperature stability, and which remain in liquid form over a wide temperature range and are relatively non-volatile at elevated temperatures.

Another object of the invention is the provision of polyfluorinated phosphate esters having the above-noted properties and other advantages, and having particular utility as hydraulic fluids or components thereof, heat transfer fluids, and as lubricants.

Other objects and advantages will appear hereinafter. We have discovered that the above-noted objects are achieved according to the invention by the provision of a class of pentafluorophenyl phosphates having the formula

where R and R' are each a member selected from the group consisting of pentafluorophenyl and alkyl. Such alkyl group includes straight chain and branched-chain alkyls and contains, for example, from 1 to about 12 carbon atoms, preferably from about 4 to about 9 carbon atoms. Thus, for example, such alkyl group can be methyl, ethyl, propyl, butyl, pentyl, hexyl, heptyl, octyl, nonyl, decyl, undecyl, dodecyl, isopropyl, isobutyl, isoamyl, 2-ethyl butyl, 1,2-dimethyl butyl, 2-methylpentyl, 1-ethylpentyl, 1-methylhexyl, 2-ethylhexyl, and the like. R and R' can be the same or different. Both R and R' can be pentafluorophenyl; both R and R' can be alkyl either the same or different; and R can be pentafluorophenyl and R' can be alkyl.

Preferred phosphate esters according to the invention are the dialkyl pentafluorophenyl phosphates having the formula

where R'' and R''' are each an alkyl group either straight chain or branched-chain, containing from 1 to about 12 carbon atoms, preferably about 4 to about 9 carbon atoms, as described above.

It has been found that the above-defined pentafluorophenyl phosphates are particularly valuable as functional fluids, e.g., as base stocks for hydraulic fluids, and are also useful as heat transfer media and as lubricants due to the advantageous physical properties of such compounds. These properties include high fire resistance, increased temperature stability, and liquidity over a relatively wide temperature range. Thus, for example, generally these fluorinated phosphate esters have a thermal stability in the range of about 400 to about 700° F., have autoignition temperatures up to and in excess of 1000° F. and remain liquid down to a temperature of the order of

2

—40 to —100° F. Further, the viscosity of such pentafluorophenyl phosphate esters at low temperatures of the order of —40 to —100° F. permits the operative use of such liquids as hydraulic fluids, cooling media and lubricants in these low temperature ranges. These compounds are also relatively non-volatile at elevated temperatures due to the high boiling point of these materials. Also, the phosphate esters of the invention, particularly the dialkyl pentafluorophenyl phosphates, have relatively low pour points, e.g., of the order of —75° F. to —100° F. or lower, which, together with the relatively low viscosity of these materials at low temperatures, permit the liquid compounds to be pumped without high expenditure of energy at low temperatures. Moreover, the phosphate esters of the invention have good hydrolytic stability, and do not adversely affect materials, such as metals, e.g., steel, copper, and the like, with which they may be in contact. These improved properties are believed to be due in large measure to the presence of the pentafluorophenyl radical or radicals in the phosphate esters of the invention.

The above-noted properties render the pentafluorophenyl phosphate esters hereof particularly useful as hydraulic fluids, lubricants and heat transfer media, e.g., cooling fluids, in aircraft systems, especially modern high-speed aircraft systems.

The monoalkyl or dialkyl pentafluorophenyl phosphate esters of the invention are produced by reacting the corresponding aliphatic alcohol with either pentafluorophenyl phosphoryl dichloride or bis(pentafluorophenyl) phosphoryl chloride, preferably in the presence of pyridine or any other suitable HCl acceptor. The proportion of HCl acceptor or pyridine generally employed is usually about equimolar with respect to the polyfluorinated alcohol. Where it is desired to prepare the preferred dialkyl pentafluorophenyl phosphate esters, pentafluorophenyl phosphoryl dichloride is used, and a proportion of about 2 moles of the alcohol to one mole of the phosphoryl dichloride is employed. Where it is desired to prepare the bis(pentafluorophenyl) monoalkyl phosphate esters, bis(pentafluorophenyl) phosphoryl chloride is used, and a portion of about one mole of the alcohol to one mole of the phosphoryl chloride is utilized. Pentafluorophenyl phosphoryl dichloride and bis(pentafluorophenyl) phosphoryl chloride are the subject of the invention of the copending application Ser. No. 364,756, filed of even date herewith, of Robert H. Boschan and James P. Holder, and the method of preparation of these compounds is described in said application.

The tris(pentafluorophenyl) phosphate esters of the invention are prepared by reacting pentafluorophenol with phosphorus oxychloride in a proportion of about 3 moles of the pentafluorophenol to one mole of the POCl_3 .

The reaction is carried out generally by heating the reaction mixture, which may also include an organic solvent, for a period of time, e.g., several hours, removing the organic phase containing the phosphate ester reaction product, preferably washing and then drying such organic material, and distilling this material, usually at low pressure, to separate the phosphate ester present from excess aliphatic alcohol or pentachlorophenol, and to remove water and any organic solvent present.

Specific examples of pentafluorophenyl phosphates of the invention are as follows:

3

Some preferred compounds of the invention are, for example, compounds (4), (5), (6), (8) and (11).

The following are examples of preparation of the compounds of the invention:

EXAMPLE 1

Dibutyl pentafluorophenyl phosphate

To a mixture of 13.8 g. (0.186 mole) of redistilled n-butyl alcohol, 14.7 g. (0.186) mole of pyridine, and 35 ml. of benzene were added dropwise with stirring 25.4 g. (0.0844 mole) of pentafluorophenyl phosphoryl dichloride. The temperature was maintained at 26°–43° C. during the addition, which was complete in 45 minutes. The mixture was mixed for 15 minutes at 30° C., then heated to reflux temperature and allowed to reflux overnight. The mixture was then cooled and poured into four times its volume of water. The bottom organic layer was drawn off and the aqueous layer was extracted with one 80 ml. portion and two 20 ml. portions of ether; these ether extracts were then added to the organic layer, which was then washed with successive 20 ml. portions of 5% hydrochloric acid, water, and 5% sodium bicarbonate. After drying over anhydrous magnesium sulfate, the solvents were evaporated on a steam bath, and the residue was distilled at 0.15–0.16 mm. mercury. The main fraction of 75

4

dibutyl pentafluorophenyl phosphate, 12.6 g. distilled at 102–106° C. (0.15–0.16 mm. mercury).

The resulting dibutyl pentafluorophenyl phosphate, compound (4) above, has a density at 77° F. of 1.24 g./ml., a kinematic viscosity at –40° F. of 263 centistokes and at –65° F. of 1432 centistokes, and a pour point below –90° F. The compound remains liquid over a broad temperature range. In addition, such phosphate has good thermal stability, high autoignition temperature, good hydrolytic stability and high fire resistance. Such phosphate serves particularly as a hydraulic fluid or lubricant in an aircraft system.

EXAMPLE 2

Bis(pentafluorophenyl) butyl phosphate

The procedure of Example 1 is substantially carried out except employing about 0.09 mole of n-butyl alcohol and about .09 mol bis(pentafluorophenyl) phosphoryl chloride, instead of the pentafluorophenyl phosphoryl dichloride.

The product produced, consisting essentially of compound (5) above, bis(pentafluorophenyl) butyl phosphate, has satisfactory viscosity at low temperatures, low pour point, good thermal stability, high autoignition temperature, good hydrolytic stability, and high fire resistance. Such phosphate is useful as a base stock for a hydraulic fluid of an aircraft system.

EXAMPLE 3

Tris(pentafluorophenyl) phosphate

To 97.2 g. (0.528 mole) of pentafluorophenol were added dropwise with stirring 153.5 g. (1.00 mole) of redistilled phosphorus oxychloride. The temperature was maintained at 20°–26° C. during the addition, which was complete in 3/4 hour. The mixture was then refluxed for one hour at 129° C., then cooled to 120° C., and maintained at 120° C. for 66 hours. The mixture was heated to 125° C. for 2 1/2 hours and then cooled. The phosphorus oxychloride was removed by distillation at atmospheric pressure. The residue was distilled at lower pressure. The tri(pentafluorophenyl) phosphate, 26.8 g., distilled at 164°–168° C. at 1 mm. mercury.

The resulting material, consisting essentially of tris(pentafluorophenyl) phosphate, compound (22) above, has good thermal stability, high autoignition temperature, good hydrolytic stability, and high fire resistance. Such phosphate is useful as a base stock component for a hydraulic fluid of an aircraft system, and as a lubricant.

EXAMPLE 4

The procedure of Example 3 is repeated, except employing 0.22 mole of pentafluorophenol and about 0.07 mole of phosphorus oxychloride, i.e., about a 3 molar ratio of the pentafluorophenol to the phosphorus oxychloride, to obtain about 11 grams of tris(pentafluorophenyl) phosphate.

EXAMPLE 5

The procedure of Example 1 is repeated, except employing a mixture of alcohols consisting of 0.09 mole amyl alcohol and 0.09 mole hexyl alcohol, instead of n-butyl alcohol. The product obtained is compound (17) above. This material has satisfactory viscosity at low temperatures, low pour point, good thermal stability, high autoignition temperature, good hydrolytic stability, and high fire resistance. Such phosphate is useful as a base stock for a hydraulic fluid of an aircraft system.

EXAMPLE 6

The procedure of Example 1 is substantially repeated, except employing the same molar amount of the following respective alcohols:

- (a) n-propyl alcohol
- (b) isobutyl alcohol
- (c) 2-ethyl butanol

- (d) 2-methyl hexanol
- (e) 2-ethyl hexanol
- (f) nonyl alcohol
- (g) 2-ethyl nonyl alcohol

The products produced are, respectively, compounds (3), (6), (8), (10), (11), (14) and (19).

Such compounds are useful as hydraulic fluids, lubricants and/or heat transfer media.

EXAMPLE 7

The procedure of Example 1 is substantially repeated, except employing about .09 mole bis(pentafluorophenyl) phosphoryl chloride and about 0.09 mole of each of the 15 respective alcohols:

- (a) ethanol
- (b) pentanol
- (c) heptanol
- (d) octanol
- (e) isononyl alcohol
- (f) 2-methyl octanol
- (g) undecanol

The products produced are, respectively, compounds (2), (7), (9), (12), (13), (15) and (18).

From the foregoing, it is seen that the invention provides a novel class of pentafluorophenyl phosphates which are designed particularly for use as base stocks or base stock components of hydraulic fluids in aircraft systems, and which are also useful as lubricants and as heat transfer or cooling media in aircraft systems.

While we have described particular embodiments of our invention for the purpose of illustration, it should be understood that various modifications and adaptations thereof may be made within the spirit of the invention, as set forth in the appended claims.

We claim:

1. A phosphate having the formula

where R and R' are each a member selected from the class consisting of pentafluorophenyl and alkyl groups.

2. A phosphate as defined in claim 1, said alkyl groups containing from 1 to about 12 carbon atoms.

3. A phosphate as defined in claim 1, said alkyl groups containing from about 4 to about 9 carbon atoms.

4. A compound as defined in claim 1, wherein R is pentafluorophenyl and R' is alkyl containing from 1 to about 12 carbon atoms.

5. A compound as defined in claim 1, wherein R is pentafluorophenyl and R' is alkyl containing from about 4 to about 9 carbon atoms.

6. A phosphate having the formula

where R'' and R''' are each an alkyl group containing from 1 to about 12 carbon atoms.

7. A phosphate as defined in claim 6, wherein said alkyl groups contain from about 4 to about 9 carbon atoms.

8. Dibutyl pentafluorophenyl phosphate.

9. Tris(pentafluorophenyl) phosphate.

10. Di(2-ethyl butyl) pentafluorophenyl phosphate.

11. Di(2-ethyl hexyl) pentafluorophenyl phosphate.

12. Diocetyl pentafluorophenyl phosphate.
